EXTENSIBLE BRUSH AND CONTAINER
THEREFOR

Walter P. Abel, Madison, N. J.

Application January 24, 1951, Serial No. 207,568

3 Claims. (Cl. 15—185)

1

This invention relates to an extensible brush and container therefor and has as its primary object, the provision of a brush which may be readily extended and/or collapsed for positioning in a container, and provided with means whereby the container may be utilized in its entirety as a handle for the brush.

An additional object of the invention is the provision of an improved brush adapted to be utilized in various positions of adjustment.

Still another object of the invention is the provision of a container for such a brush which may be readily secured thereto for use as a handle.

Another object of the invention is the provision of a hinged container for a brush whereby the top and bottom portion may be secured in extended relation and one of such portions secured to the brush providing the brush with an extension handle.

Other objects reside in the combinations of elements, arrangements of parts, and features of construction, all as will be more fully pointed out hereinafter, and shown in the accompanying drawings wherein:

Figure 1 is a top plan view of the brush and container showing the latter in extended relation and applied to the brush as a handle therefor.

Figure 2 is an enlarged sectional view taken substantially along the lines 2—2 of Figures 1 and 3 as viewed in the direction indicated by the arrows.

Figure 3 is a sectional view taken substantially along the lines 3—3 of Figures 1 and 2 as viewed in the direction indicated by the arrows.

Figure 4 is a fragmentary sectional view taken substantially along the line 4—4 of Figure 3 as viewed in the direction indicated by the arrows.

Figure 5 is a sectional view taken substantially along the line 5—5 of Figure 2 as viewed in the direction indicated by the arrows.

Figure 6 is a top plan view of the brush in folded position showing the same in the container before closure of the lid.

Figure 7 is a sectional view taken substantially along the line 7—7 of Figure 6 as viewed in the direction indicated by the arrows.

Figure 8 is a fragmentary perspective view partially broken away of a constructional detail.

Figure 9 is a fragmentary perspective view of an additional constructional detail.

Figure 10 is a fragmentary side view partially in section and partially in elevation disclosing

2

the operation of the locking means for securing the cover to the brush.

Similar reference characters refer to similar parts throughout the several views of the drawings.

Referring now to the drawings in detail, there is generally indicated at 10 a container for a brush comprising a bottom section 11 and a top section 12 hingedly secured together as by a hinge 13. The bottom section 11 is provided with a cut-away portion 14 about the rim thereof to provide a seat for the edge of top section 12 when the latter is in closed position, as best shown in Figure 7. The side portions of the rim 15 which extends above the cut-away portion 14 comprise double spaced inner and outer walls 16 and 17, respectively, including a longitudinally extending space therebetween. This space is open at one end of the container as indicated at 18 (see Figures 5 and 6) and adapted to accommodate a U-shaped metallic locking member including side portions 19 which extend between the side walls 16 and 17 and a bight portion 20 which extends across the open space between the ends of such walls.

As best shown in Figure 9 the side walls are provided with notched portions 21 extending through both inner and outer walls 16 and 17, the purpose of which will be more fully described hereinafter, while the locking strip as shown in Figure 8 includes a pair of notches 22 adjacent each of which is a longitudinally extending groove 23 formed by a pair of extending tongues 24. The notches 21 and 22 are adapted to register when the bight portion 20 is pulled outwardly to the dotted line position shown in Figure 4, but when the bight portion is pushed inwardly the tongues 24 will be disposed across the notches 21 for a purpose to be more fully described hereinafter.

As best shown in Figures 1 and 2, means are provided for securing the upper and lower sections of the case in extended position, and take the form of a link 30 pivotally secured as at 31 to either side of the end of upper portion 12 and provided with a notch adapted to engage over a corresponding stud 32 on an adjacent portion of the end wall of the lower portion 10 to lock the parts in extended position.

It will thus be seen that the casing 10 which has hitherto been described may be either closed and secured in closed position in any desired conventional manner or opened and extended to the position shown in Figures 1 and 2 and secured in such position.

Referring now in detail to the brush comprising a portion of the instant invention, it will be seen that the latter is comprised of four back portions 35, each of substantially elongated relatively flat configuration, and each provided with an elongated row of bristles 36 of any desired type. The upper portion of each member 35 is provided with a pair of longitudinally spaced pivot pins 36a to which is secured one end of a link 37, the opposite end of each link being secured to a corresponding pivot pin 36a in an adjacent back 35. The arrangement is such that the brush may be folded to the position disclosed in Figure 6 by compression of the sides which causes pivotal movement 15 of the linkage formed by the links 37 and pivots 36a to the configuration shown in Figure 6, it being pointed out that the container 10 is of sufficient length to accommodate the extending opposite ends of the backs 35. The case may then be closed as shown in Figure 7, and the assembly forms a single compact structure. Correspondingly, when it is desired to utilize the device, the backs 35 may be extended by virtue of the linkage previously described to the position disclosed in Figures 1 and 5. The brush may obviously be used in either condition if desired.

When it is desired to utilize the container as a handle, the notches 21 are seated over the link members 37 connecting the outermost backs 35, and the locking member moved by grasping the bight 29 from the dotted line position of Figure 4 to the full line position of Figure 4 whereupon the tongues 24 will underlie the outermost links 37 securely locking them in their associated notches. The portion 12 may be extended to the position shown in Figure 1 and used as an extension handle and locked in position by means of the links 30.

From the foregoing it will now be seen that there is herein provided an improved brush and container therefor which accomplishes all the objects of this invention, and others, including many advantages of great practical utility and commercial importance.

As many embodiments may be made of this inventive concept and as many modifications may be made in the embodiment hereinbefore shown and described, it is to be understood that all matter herein is to be interpreted merely as illustrative, and not in a limiting sense.

I claim:

1. An extensible brush construction comprising a plurality of elongated parallel brush backs, bristles carried by each of said backs, pivot means in each of said backs, links engaging said pivot means for pivotally securing each back

4
to an adjacent back whereby the spacing of said backs relative to each other may be varied, a casing for said brushes and means for securing said casing to said brush to serve as a handle therefor, said last-mentioned means comprising notches in the rim of said casing engaging over said links, and tongued slide means cooperating with said notches carried by said casing for engaging said links in said notches.

2. An extensible brush construction comprising a plurality of elongated parallel brush backs, bristles carried by each of said backs, pivot means in each of said backs, links engaging said pivot means for pivotally securing each back to an adjacent back whereby the spacing of said backs relative to each other may be varied, a casing for said brushes and means for securing said casing to said brush to serve as a handle therefor, said means comprising notches in the rim of said casing seating over said links, and a slide member having corresponding notches from which extend longitudinal grooves formed by extending tongues, said slide member being movable to engage and hold said links in said grooves.

3. An extensible brush construction comprising a plurality of elongated parallel brush backs, bristles carried by each of said backs, pivot means in each of said backs, links engaging said pivot means for pivotally securing each back to an adjacent back whereby the spacing of said backs relative to each other may be varied, a casing for said brushes and means for securing said casing to said brush to serve as a handle therefor, said means comprising notches in the rim of said casing seating over said links, and a slide member having corresponding notches from which extend longitudinal grooves formed by extending tongues, said slide member being movable to engage and hold said links in said grooves, said casing comprising two longitudinally hinged portions adapted when fully open to engage in end abutting relation, and means for latching the two portions in fully open position.

45 WALTER P. ABEL.
